(No Model.)

W. B. PADGETT.
HOISTING MACHINE.

No. 244,654.

Patented July 19, 1881.

UNITED STATES PATENT OFFICE.

WILLIAM B. PADGETT, OF BATESVILLE, ARKANSAS.

HOISTING-MACHINE.

SPECIFICATION forming part of Letters Patent No. 244,654, dated July 19, 1881.

Application filed May 13, 1881. (No model.)

To all whom it may concern:

Be it known that I, WILLIAM B. PADGETT, of Batesville, in the county of Independence and State of Arkansas, have invented certain useful Improvements in Hoisting-Machines, 5 of which the following is a specification.

My invention consists in a novel construction, arrangement, and combination of a platform, a hollow screw-shaft, a series of windlasses, a rope or chain, and a series of pulleys, whereby provision is made for raising and lowering weights, and for other purposes, as hereinafter more particularly described.

In the accompanying drawings, Figure 1 is 15 a side view of an apparatus embodying my improvements. Fig. 2 is a vertical section of the same. Figs. 3, 4, 5, and 6 are detail views.

A represents a frame-work of any suitable description, in which the carriage is adapted 20 to slide up and down. The carriage consists of two platforms, B B², which may be connected rigidly by posts b, as shown in Figs. 1 and 2, or detachably by means of hooked rods c and eyes or staples c², as shown in Fig. 4. 25 The frame-work A may be made in sections, as shown in Fig. 3, so that it may be taken apart and packed in small space for transportation when desired. The carriage is provided with upright posts D, which slide in ways in 30 upright portions of the frame A, and are provided with friction-rollers d. The platforms may be strengthened by diagonal braces e on their under sides.

To the top of the upper platform, B, is attached a tripod, F, in the center of the top of which is a screw-threaded hole. In this hole works a tube or hollow shaft, G, which is screw-threaded on its exterior to correspond with the threads in the tripod. At the upper 40 end of the hollow shaft is a hand-lever, g, for turning it, and on the portion below the screw-thread is a spiral groove constituting a vertical windlass, H. On the top of the platform B, journaled in posts i i, is a tapering horizontal windlass, J, on the face of which is a spiral groove. In the center of the platform B is an opening, in which is a pulley, K.

The upper end of a rope or chain, L, is secured, by a hook, l, or other suitable means,

to the top of the frame A. The rope or chain 50 is then passed down through the hollow shaft G, then around the pulley K, then around the spiral horizontal windlass J, and its lower end is secured to the vertical windlass H.

The operator on the top of the upper platform, B, by turning the hand-lever g, winds the rope or chain L around the windlass H, and thus hoists himself and the load carried on the lower platform, B².

When it is desired to use this apparatus for 60 hoisting loads on the outside of the building where it is located, the platform is rigidly secured in the frame; and instead of securing the upper end of the rope or chain to the frame, as above described, it is passed over a pulley 65 in said frame, and then carried, as shown in dotted lines, over pulleys in a bracket, M, attached to the outside of the building, so that by turning the shaft G the load outside is hoisted and the platform remains stationary. 70

Having thus fully described my invention, I claim as new and desire to secure by Letters Patent—

1. In a hoisting apparatus, the combination 75 of a rope or chain, a tubular screw-threaded shaft, a horizontal windlass, and a vertical windlass, substantially as and for the purpose herein described.

2. The combination, with the platform B and screw-threaded hollow shaft G, of the screw-threaded trevet or tripod F, as shown and described, for the purpose specified. 80

3. The combination of the rope or chain L, the tubular screw-threaded shaft G, working in the tripod F, the platform B, provided with 85 the pulley K, the horizontal tapering windlass J, and the vertical windlass H, carried by the shaft G, all arranged and operating as herein shown and described.

4. The combination of the platform B, windlasses H J, tubular shaft G, rope or chain L, and bracket M, arranged and operating as shown and described, for the purpose specified. 90

WILLIAM B. PADGETT.

Witnesses:

THOS. B. PADGETT,
MARK A. R. WYCOUGH.
